DESK SET

Filed June 6, 1929

INVENTOR:

SAMUEL A. NEIDICH.

by Arthur E. Paige,
Attorney.

UNITED STATES PATENT OFFICE

SAMUEL A. NEIDICH, OF EDGEWATER PARK, NEW JERSEY

DESK SET

Application filed June 6, 1929. Serial No. 368,892.

My invention relates to writing implements and holders therefor, including a base member having recesses to receive such implements, and particularly such sets wherein the base member represents a slab of natural mineral, such as an ornamental stone or an imitation of such stone or an imitation of an ornamental metal such as gold, silver, bronze, etc. The purpose and effect of my invention are to provide a desk set wherein the base is covered with a film of light and cheap material representing heavy costly material such as above contemplated, and to cover the writing implements or portions thereof with the same cheap material; so that the base and writing implements shall match each other.

As hereinafter described, such a result is attained by covering both a base formed of cheap material such as wood, and the writing implements or parts thereof, with a cellulose product such as celluloid, cellulose nitrate, cellulose acetate and the like. Such cellulose product manifesting a distinctive pattern either by aggregating different kinds, textures, or colors of such material or by dyeing such a cellulose product in selected regions to produce the desired pattern.

My invention includes the various novel features of procedure and structure herein-after more definitely specified.

In said drawing; Fig. I is a perspective view of a desk set embodying my invention, including a base and a writing implement matching the base.

Fig. II is a vertical sectional view of the base structure shown in Fig. I.

In said figures; the base structure includes, at the bottom thereof, a block of wood or other cheap material 1, for instance, a molded slab of plaster-of-Paris or other composition such as an aggregate of sawdust and a binding medium. Said bottom base member 1 is covered with the film 2 of celluloid or the like presenting a distinctive pattern structure at its surface, as indicated at 3 in Fig. I. For instance, such pattern may represent the markings of natural onyx, marble, or other mineral, and may be formed by aggregating cellulose products of different kinds, textures, or colors, or by merely dye-

ing such a product in selected regions to produce the desired pattern.

The upper base member 4, formed of such cheap material, is similarly covered with the film 5 of the cellulose product having distinctive pattern markings 6 matching the pattern marks 3 aforesaid.

Said base structure includes the writing implement holder 7, which may be conveniently formed of metal, including the recess 8 adapted to detachably hold a writing implement, such as the pen holder 9, in position to be readily accessible for removal. Said holder 7 has the covering 11 which is a film of the same cellulose product, presenting pattern marks 12 matching the marks 3 and 6 aforesaid.

Said three members 1, 4, and 7 of the base structure may be conveniently rigidly connected by the screw 14 which engages the threaded socket 15 in said member 7 which is prevented from turning upon the member 4 by the pin 16 extending from said member 4 into the recess 17 in said member 7. Said screw may have the lock washer 18 bearing upon the plane washer 19 in the recess 20 in said base member 1 and said recess may be covered by the film 21 of the same material as the other films aforesaid, so that the means for connecting the several elements of the base structure are covered and concealed.

As indicated in Fig. I; the writing implement 9 has films 23 and 24 of the same pattern material covering the different portions thereof; so that said writing implement matches the base structure of the desk set.

The films of cellulose products aforesaid are applied in a softened state and altho they may be softened by heating them in boiling water, I prefer to soften them by subjecting them to the action of a solvent. For instance, acetone is ordinarily employed as a solvent for celluloid and cellulose nitrate, and ethyl acetate, or a mixture of alcohol and ether, may be employed as solvents for cellulose acetate. However, celluloid and the like, when softened with acetone, are sticky and, therefore, I prefer to use a solvent having an adequate softening effect without rendering the surface of the cellulose product 100

sticky and, preferably a cellulose nitrate solvent of high boiling point and low volatility, for instance, derivatives of ethylene-glycol, such as ethylene-glycol-mono-ethyl-ether or ethylene-glycol-mono-ethyl-ether-acetate. Such solvents are preferable diluted with more or less of a fluid which has no such softening effect; in order to control such softening effect. Altho any light hydrocarbon such as gasoline or naptha may be used as such a diluent, they are inflammable and it is preferable to use a non-inflammable diluent such as carbon tetrachloride.

For instance, the films shown may be adequately softened in a bath containing twenty per cent of acetone and eighty per cent of carbon tetrachloride in which they are allowed to soak for forty-eight hours. However, they may be adequately softened in much less time by instantaneous immersion and emersion with respect to a bath including twenty per cent of ethylene-glycol derivative and eighty per cent of carbon tetrachloride, if they are allowed to rest for, say, ten minutes thereafter for the solvent to penetrate. Thereupon, ordinary celluloid thus softened may be stretched to four times its original dimensions and be permitted to resume its original shape by its own elasticity, without detriment.

Plane sheets of celluloid or the like may be thus softened and stretched over the elements 1 and 4 aforesaid. However, I prefer to form the tubular coverings 11, 23 and 24 by rolling several convolutions of extremely thin sheets of the cellulose product upon a mandrel while softened with a suitable solvent and then, while in a plastic state, stretching them over the holders 7 and 9 upon which they contract as the solvent evaporates.

However, as far as I am aware, it is broadly new to provide a desk set wherein a cellulose product of the same pattern is used as a covering for a stationary base and a writing implement which is removably supported by such base, so that the base and implement are matched in appearance. Therefore, I do not desire to limit myself to the precise details of procedure and structure herein set forth, as it is obvious that various modifications may be made therein without departing from the essential features of my invention, as defined in the appended claims.

I claim:

1. In a desk set, the combination with a base, including two distinct blocks, one above the other, respectively covered with films of artificial cellulose material concealing said blocks; of a writing implement holder, including a recess for the point of the writing implement and mounted on said base; means rigidly connecting said base and holder, including a screw extending through both of said blocks and engaging a screw threaded socket in said holder, as a nut; and means distinct from said screw connection, extend-

ing between said upper block and holder and preventing rotation of the latter.

2. In a desk set, the combination with a base comprising a bottom block and an upper block, respectively covered with films of artificial cellulose material concealing said blocks; of a metallic holder for a writing implement, including a cylindrical recess for the point of the writing implement, and mounted on said base with its axis extending obliquely upward therefrom, and means rigidly connecting said base blocks and holder and including means maintaining the axis of said recess in predetermined angular relation with said base and its surface adapted for contact with the desk.

3. In a desk set, the combination with a base including two primarily separate blocks of cheap material, respectively covered with films of artificial cellulose material concealing said block; of a holder for a writing implement, including a recess for the point of the writing implement, and mounted on said base; means rigidly connecting said base blocks and holder and adapted to prevent relative movement thereof; and a thin covering of artificial cellulose material on said base concealing said connecting means.

In testimony whereof, I have hereunto signed my name at Burlington, New Jersey, this 31st day of May, 1929.

SAMUEL A. NEIDICH.
